UNITED STATES PATENT OFFICE

HAROLD EUGENE RUGGLES, OF ROXBURY, MASSACHUSETTS

STITCH PICKER

Application filed June 30, 1931. Serial No. 547,968.

This invention relates to a stitch picker and has for its primary object to provide, in a manner as hereinafter set forth, a device of this character embodying a novel construction and arrangement of parts, for removing the sole securing stitches from a shoe after the outer or top sole has been removed.

Another important object of the invention is to provide a stitch picker of the character described embodying novel means for automatically feeding the shoe relative to a reciprocating punch when removing the stitches.

Other objects of the invention are to provide a stitch picker of the aforementioned character which will be simple in construction, strong, durable, efficient and reliable in operation and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a view in top plan view of a stitch picker constructed in accordance with the present invention.

Fig. 2 is a view in front elevation thereof.

Fig. 3 is a view in end elevation of the machine.

Fig. 4 is a view in vertical cross section taken substantially on the line 4-4 of Fig. 2, looking in the direction indicated by the arrows.

Fig. 5 is a fragmentary view in top plan showing the arrangement of the shoe engaging element relative to each other.

Fig. 6 is a detail view in perspective, of one end portion of the feed rod or device.

Referring now to the drawings in detail, it will be seen that the reference numeral 1 designates a base having mounted on one end portion thereof a pair of standards 2 provided with bearings 3 at their upper ends, in which is journaled a crank shaft 4 having grooved pulleys 5 and 6 fixed on its end portions. The pulley 5 is adapted to be opera-

tively connected with a suitable source of power (not shown).

Mounted on the other end portion of the base 1 is a pair of comparatively short standards 7 having bearings 8 at their upper ends 55 in which a crank shaft 9 is journaled. A grooved pulley 10 is fixed on one end portion of the crank shaft 9. Uprights 11 are mounted on the base 1 adjacent the standards 7, and pivotally mounted between the upper ends of said uprights is a rocker arm 12 having one end operatively connected to the crank shaft 9 for actuation thereby through the medium of a connecting rod 13.

A standard 14 is mounted on the base 1 and is provided with a curved upper end portion which terminates in a vertical bearing 15 disposed beneath the other end portion of the rocker arm 12. A punch bar 16 is mounted for vertical reciprocation in the bearing 15 70 and has its upper end portion connected to the adjacent end portion of the rocker arm 12 by a pin and slot connection 17. The lower end portion of the punch bar 16 is socketed for the reception of a punch 19 which is detachably secured in position by a set screw 20.

A pair of comparatively short standards 21 is also mounted on the base 1 in alignment with the standards 2. The standards 21 are provided with bearings 22 at their upper ends 80 in which a shaft 23 is journaled. A grooved pulley 24 is fixed on one end portion of the shaft 23 and an endless belt 25 is trained over said pulley 24 and the pulley 6 for operatively connecting the shaft 23 to the crank shaft 4 85 for actuation thereby.

Another grooved pulley 26 is fixed on an intermediate portion of the shaft 23, and an endless belt 27 is trained over said pulley 26 and the pulley 10 on the crank shaft 9 for 90 operatively connecting said crank shaft 9 to the shaft 23 for actuation thereby. A brush 28 which preferably is provided with metal bristles is fixed on the other end portion of the shaft 23 for rotation adjacent the punch 19.

A work supporting table 29 is disposed adjacent the punch 19 on a supporting leg 30 which is secured to the base 1. The table 29 is adapted for engagement with the welt 100

portion of a shoe to properly support said shoe beneath the punch 19. A clamping arm 31 is pivotally mounted on the upper end of a standard 32 for swinging movement above the table 29 for engagement with the shoe in a manner to shiftably retain said shoe in position on the table 29. A coil spring 33 has one end connected to the standard 32 and its other end connected to an intermediate portion of the clamping arm 31 for yieldingly urging said clamping arm against the shoe.

The reference numeral 34 designates a guard which is disposed adjacent the brush 28 and the punch 19, said guard being mounted on the upper end of a supporting leg 35 which is mounted on the base 1.

A feed rod 36 is mounted for horizontal reciprocation on the base 1 in the brackets 37. A feed finger 38 is formed on one end of the feed rod 36, said feed finger terminating in a pointed free end portion adapted for engagement with the shoe in a manner to feed said shoe in one direction across the table 29 beneath the punch 19. At its other end, the feed rod 36 terminates in an end portion 39 of polygonal cross section having a series of threaded openings 40 extending transversely therein in which a pin 41 is selectively insertible.

The pin 41, of course, projects from one side of the polygonal portion 39 then has its free ends provided with a slot for receiving a suitable tool such as a screw driver, for placing said pin in the openings 40, or removing said pin therefrom. A bell crank lever 42 is mounted for swinging movement in a vertical plane on a bracket 43. A connecting rod 44 operatively connects the bell crank lever 42 to the crank shaft 4 for actuation thereby through the medium of a hinged free end portion 45 having a pin and slot connection 46 with the bell crank lever. The other arm of the bell crank lever is arcuate and the free end portion thereof is adapted for engagement with the pin 41 for actuating the feed rod 36 in one direction.

A coiled spring 47 has one end connected to the free end of the portion 39 of the feed rod 36, and its other end connected to a bracket 48 on the base 1 for yieldingly urging the feed rod 36 in the opposite direction.

When the machine is in use, the feed finger 38 engages the welt of the shoe and moves said shoe across the table 29 beneath the punch 19 in an alternating or step by step fashion for disposing the holes through which the stitches pass properly beneath the punch 19, as will be understood. The brush 28 removes the threads which may cling to the shoe after being punched out of the holes, by the element 19.

It may be well to here call attention to the fact that the standards 2 are curved at their upper end portions in a manner similar to

It is believed that the many advantages of a machine in accordance with this invention will be readily understood, and although the preferred embodiment of the invention is as illustrated and described, it is to be understood that changes in the details of construction, and in the combination and arrangement of parts, may be resorted to which will fall within the scope of the invention as claimed.

Having thus described my invention, what I claim as new is:—

1. A shoe sole stitch picker comprising, in combination, a base, a punch mounted for vertical reciprocation on the base, a work supporting table on the base adjacent the punch, a rotary shaft mounted on the base, a brush fixed on the shaft adjacent the punch for operative engagement with the work, means for actuating the shaft, a crank shaft rotatably mounted on the base, means operatively connecting the punch to the crank shaft for actuation thereby, and means operatively connecting the crank shaft to the first-named shaft for actuation thereby.

2. A shoe sole stitch picker comprising, in combination, a base, a standard mounted on the base, a punch mounted for vertical reciprocation on the standard above the base, a work supporting table on the base adjacent the punch, a rotary shaft mounted on the base, a brush fixed on one end portion of the shaft adjacent the punch for operative engagement with the work, means for actuating the shaft, a crank shaft rotatably mounted on the base, means operatively connecting the crank shaft to the first-named shaft for actuation thereby, a rocker arm mounted for swinging movement in a vertical plane above the base and having one end operatively connected to the punch for actuating said punch, and a connecting rod operatively connecting the outer end of the rocker arm to the crank shaft for actuation by said crank shaft.

3. A shoe sole stitch picker comprising, in combination, a base, a punch mounted for vertical reciprocation on the base, a work supporting table on the base adjacent the punch, a crank shaft mounted for rotation on the base, means operatively connecting the punch to the crank shaft for actuation thereby, a feed rod mounted for reciprocation on the base, a feed finger on the rod engageable with the work in a manner to feed said work beneath the punch in a step by step fashion, a pin projecting laterally from one end portion of the feed rod, a bell crank lever mounted for swinging movement on the base and having one end operatively engageable with the pin in a manner to move the feed rod in one direction, means operatively connecting the bell crank lever to the crank shaft for actuation thereby, and a spring connected to the feed rod for yieldingly urging said feed rod in the opposite direction.

4. A shoe sole stitch picker comprising, in combination, a base, a punch mounted for vertical reciprocation on the base, a work supporting table on the base adjacent the punch, a rotary shaft mounted on the base, a crank shaft rotatably mounted on the base, means operatively connecting the first-named shaft to the crank shaft for actuation thereby, a brush fixed on one end portion of the first-named shaft adjacent the punch for operative engagement with the work, another crank shaft rotatably mounted on the base, means operatively connecting the punch with the second-named crank shaft for actuation thereby, a feed rod mounted for reciprocation on the base, means on the feed rod operatively engageable with the work in a manner to feed said work beneath the punch in a step by step fashion, and means for actuating the feed rod.

5. A shoe sole stitch picker comprising in combination, a base, a punch mounted for vertical reciprocation on the base, a work supporting table on the base adjacent the punch, a rotary shaft mounted on the base, a crank shaft rotatably mounted on the base, means operatively connecting the first-named shaft to the crank shaft for actuation thereby, a brush fixed on one end portion of the first-named shaft adjacent the punch for operative engagement with the work, another crank shaft rotatably mounted on the base, means operatively connecting the second-named crank shaft with the first-named shaft for actuation thereby, a feed rod mounted for reciprocation on the base, means on the feed rod operatively engageable with the work in a manner to feed said work beneath the punch in a step by step fashion, and means for actuating the feed rod.

6. A shoe sole stitch picker comprising in combination, a base, a punch mounted for vertical reciprocation on the base, a work supporting table on the base adjacent the punch, a rotary shaft mounted on the base, a crank shaft rotatably mounted on the base, means operatively connecting the first-named shaft to the crank shaft for actuation thereby, a feed rod mounted for reciprocation on the base, means on the feed rod operatively engageable with the work in a manner to feed said work beneath the punch in a step by step fashion, means for actuating the feed rod, the last-named means comprising a pin projecting laterally from one end portion of the feed rod, a bell crank lever mounted for swinging movement on the base and having one end portion operatively engageable with the pin in a manner to actuate the feed rod in one direction, means operatively connecting the other end portion of the bell crank lever with the first-named crank shaft for actuation thereby, a coil spring connected with the feed rod for yieldingly urging said feed rod in the opposite direction, and a clamp arm pivotally mounted on the base for swinging movement in a vertical plane above the work-supporting table for engagement with the work in a manner to shiftably retain said work on the table.

In testimony whereof I affix my signature.
HAROLD EUGENE RUGGLES.
